UNITED STATES PATENT OFFICE.

AMOS H. WILCOX, OF BEAVER CITY, NEBRASKA, ASSIGNOR OF ONE-FOURTH TO
CHARLES T. KEATH, OF BEAVER CITY, NEBRASKA.

WIRE TIGHTENER AND SPLICER.

Application filed November 25, 1921. Serial No. 517,686.

To all whom it may concern:

Be it known that I, AMOS H. WILCOX, a resident of Beaver City, county of Furnas, State of Nebraska, and a citizen of the United States, have invented certain new and useful Improvements in Wire Tighteners and Splicers, of which the following is a specification.

My invention relates to a wire tightener and splicer, the object being to construct a device of this character whereby the broken ends of the wire may be drawn together and held while the additional piece of wire is used to securely fasten the ends together.

15 Fig. 1 is a plan view of the device;

Fig. 2 is an edge view thereof;

Fig. 3 is a view showing the manner of applying the device for use, and

20 Fig. 4 shows a similar view wherein the wires have been drawn together and securely fastened.

The stretcher preferably consists of bar 1 of sufficient length to provide ample leverage when in use. As indicated one end of the bar is fairly broad and preferably pivoted on one side thereof near the end is the pivoted member 2 having secured thereto a gripping device 3 capable of gripping one of the loose ends 5 of the broken wire.

25 The numeral 6 indicates a companion member pivotally arranged on the same side of the bar on the member 2, but on the opposite edge, it likewise being provided with a gripping member 7 capable of gripping

30 the other loose ends of the broken wire. The outer end of the bar 1 is provided with a hook 9 which is adapted to engage one of the broken wires when the bar is drawn into horizontal position thereby holding the

35 device in this position in order that the necessary splicing may be made between the broken wire. As a convenient means for taking up the slack in the wires preparatory to finally securing them together, I

40 preferably provide a set of auxiliary hooks 10-10 which are arranged on the opposite side of the bar 1 upon the pivots of the first mentioned set of hooks. Each of these auxiliary hooks is preferably of one piece

45 being bent at the outer ends and notched as at 11 whereby they are adapted to catch the wires regardless of the barbs of the wire to

take up the initial slack, after which the bar 1 is reversed and the first set of hooks brought into use, the gripping member being of such a construction as to grip back of the barbs, or by means of the looped ends of the wire whereby the final tightening may be effected and the two wires thereafter be spliced together.

50 In actual use the bar 1 is brought into a vertical position and the gripping hooks 10-10 are attached to the wires to take up the slack. The bar 1 is then reversed and the gripping members 3 and 7 are attached to the wire and the final tightening thereof is effected. As illustrated in Figures 3 and 4, the gripping members on one edge of the bar 1 are placed inwardly quite a distance from the end of the bar 1 assuming an overlapping position relative to each other. The purpose of this is to have the gripping members overlap when the bar is drawn into horizontal position as illustrated in Figure 75

70 4 wherein the ends of the wire are substantially aligned horizontally and brought together. In this position the hook 9 is attached to the adjacent wire and an additional wire 10' is spliced to the ends of the

75 broken wire thereby securely fastening the

80 wires together after which the gripping members are detached and the device removed.

I claim:

85 A wire stretcher including a lever, a primary pair of gripping devices pivotally secured on one side of said lever, adjacent the edges thereof in staggered relation, pivotal means for said primary gripping devices arranged in staggered relation on said lever, 90 said pivotal means extending through the lever to the opposite side thereof, and a secondary pair of gripping devices pivotally secured to said pivotal means on the opposite side of the lever from the primary 95 gripping devices, said primary gripping devices having notched, hooked ends for initially engaging and stretching the wire, and said secondary gripping devices having hooked ends for secondarily receiving and 100 tightening the stretched wire.

In testimony whereof I hereunto affix my signature.

AMOS H. WILCOX.
